PUMPING APPARATUS

Win W. Paget, Michigan City, Ind., assignor to
 Sullivan Machinery Company, a corporation
 of Massachusetts

Application January 5, 1937, Serial No. 119,123

21 Claims. (Cl. 230—3)

My invention relates to pumping apparatus, and from certain aspects, to controlling systems for motor driven pumping apparatus.

To maintain a narrow range of pressure conditions with a motor driven pumping apparatus when the system in which the conditions are to be maintained is subject to widely varying influences, is an important problem. For example, to maintain a certain vacuum in a system under 10 conditions when the influx of air or other fluid to the system may be varying widely in rate, or to maintain a relatively close range of pressures in a receiver when the number of air users and their rates of air consumption vary, is a problem 15 not simple, but of real importance.

An object of my invention is to provide an improved apparatus effective to maintain, in the face of varying conditions affecting the pressure in a system, a relatively close range of pressures 20 in the system. A more specific object is to provide an improved motor driven pump control system providing for pump speed control to maintain desired pressure conditions. A further object is to provide an improved motor driven pump 25 control system providing for, so to speak, normal pressure control by regulating pump speed, and upon extreme variations in system pressure, providing for unloading, desirably attended by further speed regulation. Yet another object of my 30 invention is to provide an internal combustion engine driven pump having improved controlling apparatus employing in an improved manner engine intake-manifold vacuum and pressure conditions at the service side of the pump for controlling the operation of the apparatus. Still a 35 further object of the invention is to provide an improved internal combustion engine driven pump having improved controlling means operative to regulate the engine speed. Other objects and advantages of the invention will hereinafter more fully appear.

In the accompanying drawing, in which for purposes of illustration two illustrative embodiments which my invention may assume in practice, together with a further modification, are shown:

Fig. 1 is a view, primarily in side elevation, showing a motor driven compressor in which my invention is in one of its illustrative forms embodied.

Fig. 2 is an enlarged vertical longitudinal section through a controlling apparatus constructed according to the first illustrative embodiment of the invention.

Fig. 3 is an enlarged vertical section through

a valve forming a portion of the mechanism illustrated in Fig. 2.

Fig. 4 is a detail view showing a butterfly type throttle valve.

Fig. 5 is another vertical section showing a 5 modified embodiment of the invention.

Fig. 6 is a fragmentary view in vertical section, showing a further modification.

An understanding of the invention will be facilitated if it be borne in mind that the intake vacuum of an internal combustion engine varies inversely with the speed, and inversely with the load in horsepower. For example, it is a common experience to find a windshield wiper slow down or stop when an effort is made to maintain the same speed uphill that had been maintained on a level, and also to find the wiper slowing down as speed on the level is increased. These relationships are realized with a relatively constant torque load, such as an air compressor. 10 15 20

Now referring to the drawing, and first to Fig. 1, it will be noted that a base 1 supports a pump 2, herein an air cooled compressor, and a driving motor 3 for the compressor. A radiator 4 for the cooling water for the engine 3 is provided, and a gasoline or other fuel tank 5 is mounted at the opposite end of the base 1 from the radiator 4. The engine and compressor are arranged in line for direct drive by the former of the latter; and as the engine may assume any suitable form, its 25 30 35 details of construction need not be described or illustrated, other than to point out that it is provided with an exhaust manifold 6 and an intake manifold 7. The engine may be provided, if desired, with any suitable and well known form of throttle control for preventing over-speed operation, and such a device is shown in outline at 8, 9. As its details are immaterial to the present invention, they will not be further illustrated or described. The compressor may be provided with any suitable type of unloading apparatus, and is herein shown as provided with a pressure-operable inlet valve opening device for the purpose of effecting unloading, there being, since the compressor is of the two-cylinder type, two 40 45 such devices provided. Such devices are well known and so need not be further illustrated or described. An illustration of one such device may be found in Fig. 5 of the L. J. Clapp Patent No. 2,026,300, granted Dec. 31, 1935. 50

For the purpose of controlling the compressor driving motor and unloading the compressor when occasion for that exists, I have provided the improved controlling apparatus generally designated 10. This comprises casing parts 11 55

and 12 cooperating to clamp between them a flexible diaphragm 13, normally maintained in a bowed condition, more or less as shown in Fig. 2, by a spring 14. The diaphragm 13 is subjected 5 on one side continuously to atmospheric pressure through a passage 15, and its other side is subjected to a varying pressure which is the result of the engine intake manifold pressure and a variable admission of air accomplished as will 10 shortly be described. The intake manifold 7 is connected by a suitable tube 17, manually adjusted needle valve 17', and passage 18, with the space to the left of the diaphragm 13 in Fig. 2. With this space there also communicates, through 15 a passage 19, a bore 20 and a passage 21 controllable by a suitable flow-controlling valve 22 when desired, a source of clean air at atmospheric pressure. To provide clean air for this last supply is possible in numerous ways, as for 20 example, leading a connection to the air cleaner 23 for the motor, providing a separate air cleaner, etc. Within the bore 20 there is supported an adjustable sleeve 25 providing an abutment for the lower end of a spring 26 whose upper end 25 engages a support 27 on which a diaphragm 28 rests. This diaphragm is clamped between the casing element 11 and a detachable head 29. The support 27 carries a valve element 30 having a tapered lower end 31 adapted to cooperate with 30 a coaxial opening 32 with which the passage 21 communicates. Receiver pressure, i. e. the pressure to be regulated or controlled, is conducted by a passage 33 to act upon the upper surface of the diaphragm 28.

35 The member 25 is adjustable vertically by an adjusting screw 34 and a lock nut 35. A bore 36 formed in the casing member provides a guide for a hollow member 37 to which the diaphragm 13 is secured, and a connecting element 40 connects the member 37 with the upper arm 39 of a rocking member 40 pivoted at 41 and connected at its lower end 42 by a link 43 to a butterfly valve 44 associated with the engine carburetor.

45 The receiver supply connection 33 has a branch 46 opening into a valve casing 47 in which there is arranged a valve 48 controlling the communication between the chamber 47' and a passage 49, the latter leading through a tubing 50 to the 50 pressure operable inlet valve opening device of the compressor. A plunger 51, which does not seal communication between the passage 49 and the atmosphere, is actuatable by an adjustable screw member 52 carried by the arm 42 of the 55 pivoted element 40. A spring 53 and receiver pressure normally maintain the valve 48 closed, in which position the pressure operable inlet valve opening devices are vented to atmosphere, with the result that the compressor is loaded; 60 and accordingly, except when 52 engages the plunger 51 and moves valve 48 to open position, there is no unloading.

The mode of operation of the device as so far described may now be readily understood. It 65 will be appreciated that rising receiver pressure acting upon the diaphragm 28 tends to close the valve 31 and thereby diminish the rate at which air may obtain entrance past 22 and through 21, 32, 20 and 19 into the space to the left of the diaphragm 13. Accordingly, if the same vacuum is maintained in the intake manifold 1, increasing receiver pressure will result in a higher vacuum in the space to the left of the diaphragm 13, and accordingly, movement of that diaphragm towards the left, with a resultant

turning of the device 40 counter-clockwise and a closing movement of the butterfly throttle valve 44. Likewise, if the receiver pressure should remain unchanged, and accordingly there should be no variation on that account of the position of the valve 31, an increase in intake manifold vacuum would cause a leftward movement of the diaphragm 13 and likewise a closing movement of the butterfly throttle valve 44. It will be appreciated that for a given tension of the spring 26, an increase in engine manifold vacuum without any change in the compressor discharge pressure will cause a reduced pressure beneath the diaphragm 28, and, accordingly, a further closing tendency of the valve member 31; and this 15 is a very helpful result, as will shortly be explained.

Obviously, inward adjustment of the screw 34 will make a higher receiver pressure necessary to effect a given closing of the valve 31, and a lowering of the member 25 will result in a lowered receiver pressure being effective to produce a given closing movement of the valve member 31. For wide changes in desired receiver pressure, it is better to change the spring 26, but a 25 very substantial range of adjustment is possible with any given spring.

Now the mode of operation of this apparatus may be understood from what has been said above. If the valve 22 be closed and the engine 30 spun to start it, no air will obtain admission into the space to the left of the diaphragm 13, and the intake manifold vacuum will cause the diaphragm 13 to move far to the left and swing the pivoted member 40 to a position in which the compressor will be unloaded, provided there is any receiver pressure, and a rich mixture will be supplied to effect starting of the engine. Opening of the valve 22 will then result in a reduction in the vacuum to the left of the diaphragm 13 and the member 40 may therefore swing to a position to effect interruption of contact between the screw 52 and the plunger 51, closure of the valve 48, and loading of the compressor. Now, bearing in mind what has been 45 previously pointed out, namely, that the intake manifold vacuum varies inversely with the load, it will be appreciated that as the load upon the engine increases, due to loaded operation, the intake manifold vacuum will fall, and accordingly the diaphragm 13 will be moved further 50 towards the right and open the throttle valve 44 further and further and provide the necessary admission of gaseous mixture to maintain the 55 operation of the engine.

When the pressure at the discharge side of the compressor reaches the point above which it is not desired to compress, this pressure acting upon the top of diaphragm 28 causes closing movement of the valve 31, which permits the engine 60 manifold vacuum to lower the pressure in 19 and effect leftward motion of diaphragm 13, with resultant closing movement of the engine throttle to reduce engine speed to the predetermined minimum for idling, and at the same time the 65 compressor is unloaded through the action of screw 52, through plunger 51 on valve 48, enabling compressor discharge pressure to pass to and operate the unloading devices.

The function of resumption of pumping or 70 compressing when the service line pressure reaches the predetermined minimum desired occurs as follows: Spring 26 is able to overcome the reduced receiver pressure acting upon the top of the diaphragm 28 and effect opening

movement of valve 31, with a resultant rising of the pressure in chamber 19, so that the diaphragm 13 moves to the right, opening the engine butterfly throttle valve and causing loading of the compressor by permitting closing of valve 48 and venting of pressure past 51, as previously explained.

In Fig. 5 there is shown a modified arrangement in which the space relation of the parts 10 is adapted to very convenient adaptation to the engine carburetor, unloading apparatus, etc. In this form it will be observed that the casing 10' is made up of a portion 11' and a somewhat simplified clamping portion 12' provided with 15 ribs 60 supporting a guiding portion 61. The diaphragm 13' is engaged by a spring 14', and the modification first illustrated may be materially simplified by having a push rod 63 acted upon by the left-hand side of the diaphragm 13' 20 suitably connected, as at 64, with a link 65 leading directly to a carburetor butterfly valve actuating lever 66. This lever at its lower end carries an adjustable screw 67 adapted to engage the stem 51' of an unloading device controlling valve 25 similar to that shown in Fig. 3. It will be observed that the reversals of movement and all 30 need for any complication of levers, linkages and the like, are avoided by this modification. As the mode of operation will be, however, wholly 35 clear from what has been pointed out with respect to the construction of Figs. 1 to 3, detailed explanation is unnecessary, and it will be sufficient to point out that in this case the vacuum produced at the right side of the diaphragm 13' results in movement of the latter to the right to 40 effect closing movement of the butterfly throttle valve instead of there being the necessity for motion-reversing devices, as in the apparatus of Fig. 2.

In Fig. 6 a modified construction is illustrated, in which the effect of receiver pressure is augmented in its controlling function and the effect of increased vacuum resulting from closure of the valve 31 is diminished in its controlling 45 function. The manner in which this is accomplished will be readily understood when it is noted that the member 30 is provided at its uppermost end with a relatively large diaphragm 28' subjected to receiver pressure through the connection 33' and having its lower side vented, as at Vent. The upper end of the bore 20' is closed by a smaller diaphragm 70 connected to the member 30 and subjected at its upper side to atmospheric pressure, through the Vent, and at 50 its lower side to pressure conditions within the chamber 20'. It will be noted that the diaphragm 70 is clamped in position by an intermediate head member 71, while the head member 29' clamps the diaphragm 28' between the intermediate head member 71 and itself. With this 55 form of apparatus, the cumulative effect of the increase in vacuum within the chamber 20' as the valve 31 moves towards its seat is diminished and the device is made more nearly completely responsive to compressor discharge pressure acting upon the enlarged diaphragm 28'.

It may be noted that this apparatus will be effective to control the speed of the gas engine driving the compressor in such a fashion that 60 the engine speed will, as it were, be related to the receiver pressure in a very desirable manner, and any reasonable desired range of pressure variation between maximum speed and unloading can be secured. It will be observed, moreover, that when unloading takes place there

will be at once a distinct increase in engine speed, and so an increase in manifold vacuum—an increase of several pounds per square inch; and this increased vacuum, acting upon both diaphragm 13 and diaphragm 28, will make necessary a further material reduction in receiver pressure before speeding up of the engine will occur and reloading take place. Of course, the degree to which diaphragm 13 can cause throttle closure will be controlled by any suitable stop, 5 such as usually determines the idling speed of the engine. It will be appreciated that if it were desirable to admit air in small quantity directly into the chamber 20, independently of the valve 31, to alter the vacuum differential between that 10 at slowest speed loaded operation and "no load" 15 idling operation, this could readily be done by providing a valve-controlled direct passage into the space connected with the engine intake.

Obviously, I have provided an improved control system for internal combustion engine 20 driven compressors, regulating the same according to the compressor discharge pressure most effectively, effecting unloading as needed, of 25 simple construction, and positive in action.

While I have in this application specifically 30 described two forms and a modification which my invention may assume in practice, it will be understood that these forms are shown for purposes of illustration, and that the invention may 35 be further modified and embodied in various other forms without departing from its spirit or the scope of the appended claims.

What I claim as new and desire to secure by 35 Letters Patent is:

1. In combination, a pump, an internal combustion driving engine therefor connected thereto in driving relation, unloading means for said pump, a throttle for said engine, and means made operative by engine intake vacuum for 40 controlling said throttle and said unloading means.

2. In combination, a pump, an internal combustion driving engine therefor connected thereto in driving relation, unloading means for said 45 pump, a throttle for said engine, and means made operative by engine intake vacuum for controlling said throttle and said unloading means and operative to effect unloading only after reduction in engine speed to a relatively 50 low value.

3. In combination, a pump, an internal combustion driving engine therefor connected thereto in driving relation, a throttle for said engine, and means made operative by engine intake 55 vacuum and continuously controlled by pump discharge pressure for controlling pump delivery through engine speed.

4. In combination, a pump, an internal combustion driving engine therefor connected thereto in driving relation, a throttle for said engine, and means made operative by engine intake 60 vacuum and continuously controlled by pump discharge pressure for controlling pump delivery through engine speed, said means including an operative element in communication at one side with the engine intake and having a controlled connection at its same side with a source of air.

5. In combination, a pump, an internal combustion driving engine therefor connected thereto in driving relation, a throttle for said engine, and means made operative by engine intake vacuum and continuously controlled by pump discharge pressure for controlling pump delivery 70 75

- through engine speed, said means including an operative element in communication at one side with the engine intake and having a connection at its same side with a source of air constantly regulated by pump discharge pressure.
6. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable gradually to regulate the flow area through said last mentioned connection, means for biasing said valve in an opening direction, and means continuously subjected to pump discharge pressure for moving said valve in a closing direction.
7. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable gradually to regulate the flow area through said last mentioned connection, a pump-discharge-pressure-pressed element for moving said valve in a closing direction, means for continuously subjecting said element to discharge pressure, resilient means for opposing closing movement of said valve, and means for adjusting the pressure exerted by said resilient means.
8. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable to regulate the flow area through said last mentioned connection, an element subjected on its opposite sides respectively to pump discharge and chamber pressures for moving said valve in a closing direction, and means for opposing closing movement of said valve.
9. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable gradually to regulate the flow area through said last mentioned connection, an element continuously subjected on its opposite sides respectively to pump discharge and chamber pressures for moving said valve in a closing direction, resilient means for opposing closing movement of said

valve, and means for adjusting the pressure exerted by said resilient means.

10. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable to regulate the flow area through said last mentioned connection, a pump discharge pressure subjected element for moving said valve in a closing direction, means for continuously subjecting said element to discharge pressure, a further element subject to atmospheric pressure and to variable chamber pressure on its opposite sides for moving said valve in a closing direction, resilient means for opposing closing movement of said valve, and means for adjusting the pressure exerted by said resilient means.

11. In combination, a pump, an internal combustion engine connected in driving relation with said pump, a throttle for said engine, pump unloading means, means providing a chamber having a movable wall, means normally biasing said wall in a direction to increase the size of said chamber, a connection between said wall and said throttle such that movement of said wall in said direction opens said throttle, means for effecting unloading operation of said pump unloading means upon predetermined opposite movement of said wall, a suction connection between said chamber and the engine intake, a connection for admitting fluid to said chamber, a valve movable to regulate the flow area through said last mentioned connection, a pump discharge pressure subjected element for moving said valve in a closing direction, means for continuously subjecting said element to discharge pressure, a further element subject to atmospheric pressure and to variable chamber pressure on its opposite sides for moving said valve in a closing direction, resilient means for opposing closing movement of said valve, and means for adjusting the pressure exerted by said resilient means.

12. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, unloading means also controlled by such movement of said wall, a suction connection between said chamber and the engine intake, a connection for admitting fluid to said chamber, a valve movable gradually to regulate the flow area through said last mentioned connection, a continuously pump discharge pressure pressed element for moving said valve in a closing direction, and means for yieldingly opposing closing movement of said valve.

13. In combination, a pump, an internal combustion driving engine therefor, a throttle for said engine, and controlling means for said throttle including means for subjecting it to a closing force and means for determining said closing force by a partial vacuum varying substantially continuously with engine intake vacuum and pump discharge pressure.

14. In combination, a pump, an internal combustion driving engine therefor, a throttle for said engine, and controlling means for said throttle including an element operatively connected with said throttle, and means for subjecting the same to a throttle-closing pressure varying directly and substantially continuously with pump discharge pressure and engine intake vacuum.
15. In combination, a pump, an internal combustion engine connected in driving relation with said pump, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable to regulate the flow area through said last mentioned connection, an element continuously subjected on its opposite sides respectively to pump discharge and atmospheric pressures for moving said valve in a closing direction, a further element subjected to atmospheric pressure and to chamber pressure on its opposite sides for moving said valve in a closing direction, resilient means for opposing closing movement of said valve, and means for adjusting the pressure exerted by said resilient means.
16. In combination, a pump, an internal combustion engine connected in driving relation with said pump, a throttle for said engine, pump unloading means, means providing a chamber having a movable wall, means operatively connecting said throttle to said movable wall, means continuously urging said wall in a direction to increase the size of said chamber and to open said throttle, a connection between said chamber and engine intake whereby a vacuum may be produced in the chamber to effect movement of said wall in a direction to reduce the size of said chamber and to close said throttle, means operated after a predetermined movement of said wall in said last mentioned direction for effecting operation of said pump unloading means, a connection for admitting fluid to said chamber, a valve movable to regulate the flow area through said last mentioned connection, an element continuously subjected to discharge pressure for moving said valve in a closing direction, and means for opposing closing movement of said valve.
17. In combination with an internal combustion engine, a throttle for said engine, means providing a chamber having a movable wall, means normally biasing said wall in a direction to increase the size of said chamber, a connection between said wall and said throttle such that movement of said wall in said direction opens said throttle, a suction connection between said chamber and the engine intake, a connection for admitting fluid to said chamber, a valve movable to regulate the flow area through said last mentioned connection, an element continuously subjected to discharge pressure for moving said valve in a closing direction, and means for opposing closing movement of said valve.
18. In a speed controlling mechanism for a motor driven compressor, a casing having chambers therein, pressure responsive means movable relative to said chambers respectively and forming walls thereof, an element movable to affect motor operation, means to connect one of said pressure responsive means to said element, means to connect one of said chambers to 15 atmosphere, and means controlled by the pressure responsive means forming a wall of the other chamber to regulate the flow through said connecting means between the first chamber and the atmosphere.
19. In a speed controlling mechanism for a motor driven compressor, a casing having chambers therein, pressure responsive means movable relative to said chambers respectively and forming walls thereof, an element movable to affect 20 motor operation, means to connect one of said pressure responsive means to said element, means to connect to atmosphere the chamber with which the pressure responsive means last mentioned is associated, and means controlled by the pressure responsive means forming a wall of the other chamber to regulate the flow through said connecting means between the first chamber and the atmosphere.
20. In a speed controlling mechanism for a motor driven compressor, a casing having chambers therein, pressure responsive means associated with each chamber, an element movable to effect motor speed, means to connect one of said pressure responsive means to said element, means to control movement of the pressure responsive means connected to said element, and means associated with the pressure responsive means associated with the other chamber to actuate the last-mentioned means.
21. A speed controlling apparatus for a motor driven compressor having speed controlling means, said apparatus comprising a casing having one chamber subjected to the discharge pressure of the compressor and a second chamber subjected to intake manifold pressure from the motor which drives the compressor, pressure responsive means associated with each chamber, means to transmit movement of the pressure responsive means associated with the second chamber to the speed controlling means, means to admit atmosphere to the second chamber, and means actuated by the pressure responsive means associated with the first chamber to control flow through said last-mentioned means.
